WOMAN'S UNDERGARMENT

Lillian B. Pruitt, Chattanooga, Tenn.

Application October 17, 1935, Serial No. 45,480

1 Claim. (Cl. 2—71)

The present invention relates to women's undergarments, and it is particularly concerned with women's undergarments of the "combination" variety.

5 It has previously been proposed to make combined undergarments, so as to reduce the number of individual garments worn. However, most of the garments heretofore proposed are of such a complicated character that they are more cumbersome and bulky to wear, are more costly, and are more difficult to launder, than individual garments. The garments of the prior art are also objectionable because they do not fit the form of the wearer and in general fail to perform the 10 purposes sought to be attained by a combination garment.

In the garments of the prior art there has been no attempt to provide a simple structure, and to eliminate unnecessary or duplicated parts, 20 but such garments rather represent the attempt to sew together various individual garments, without regard to fit or practicability.

It is accordingly the primary object of my invention to provide a novel undergarment which 25 efficiently combines, in a single garment a brassière, slip and step-in, which fits the form, supports the busts of the wearer, fits snugly about the hips and over the abdomen, and yet is low in cost and may be readily laundered.

30 It is another important object of my invention to devise a combination undergarment which provides a brassière, a slip and a step-in and yet which is made of what is essentially a single piece of material, which is light in weight so that it 35 may be easily packed in a small space for travel, and which may be readily donned, thus saving time in dressing.

Further objects of the invention will become 40 apparent as the specification proceeds in connection with the annexed drawing and from the appended claim.

In the drawing:

Figure 1 is a front view of my novel garment illustrating the manner in which it is worn; 45 Figure 2 is a rear view of the garment shown in Figure 1;

Figure 3 is a front view of my garment laid out flat to show the details of its construction;

Figure 4 is a sectional view taken on the line 50 4—4 of Figure 3, looking in the direction of the arrows;

Figure 5 is a fragmental sectional view taken on line 5—5 of Figure 3; and

Figure 6 is a fragmental sectional view taken 55 on line 6—6 of Figure 3.

With continued reference to the drawing, wherein like reference characters are employed to designate like parts throughout the several views thereof, my garment comprises generally an upper waist section A, a step-in section B and 5 a skirt section C.

The upper waist section in which the brassière is formed is made up of a plurality of pieces of elastic material 10, such as net, knitted material, or the like. The pieces are cut to provide 10 a form-fitting bust supporting section and are sewed together at 11 and the seams are preferably covered by tapes or strips of lace 12.

The front part of section A is provided with a pair of bust-pocket forming sections 13 which 15 are formed by folding material 10 upon itself and stitching the folds at 14, as seen in Figure 4.

Upper waist section A may be provided with a décolleté or low back if desired, but in the present instance I have for simplicity shown a back of 20 ordinary height, and it is preferably provided with a vertical opening 15, closed by any suitable form of fasteners such as hooks and eyes 16.

Slip C and step-in section B are secured to the lower edge of upper waist section A substantially 25 at the hip-line, as seen in Figure 5 by stitches 17, and in this figure the thickness of the material has been exaggerated in order to more clearly illustrate the manner in which the parts are united. 30

Step-in section B comprises a front piece 19 and a rear piece 20 which preferably extend substantially from side to side of the garment, as seen in Figures 3 and 6. By making pieces 19 and 20 extend from side to side, and securing their upper 35 edges at all points to the lower edges of pieces 10, any pull exerted by the step-in is distributed to the entire lower edge of the brassière section so as to avoid developing wrinkles in sections A and C in the region of their joinder. As seen in 40 Figures 1, 2 and 3, the upper waist section closely fits the body so as to exert a confining action thereupon. This feature also causes the upper waist section to derive considerable support from the body, thereby relieving the shoulder-strap 45 load and also insuring that the lower edge of the upper waist section will lie straight and smooth which in turn insures that the upper edges of the skirt and step-in sections will lie flat against the body without pulling or bunching. 50

The lower ends of pieces 19 and 20 taper as seen in Figures 1, 2 and 3, and a strap 21 is connected to rear piece 20. Strap 21 is detachably fastened to front piece 19 by means of snap fasteners 22 or the like. 55

From the above description it is seen that I have provided a form fitting combination under-garment which fulfills all of the requirements of brassière, slip and step-in, and yet which is of 5 simple design and construction and fits the body closely and allows freedom of movement.

The garment is slipped over the head and strap 10 then fastened in place, and hooks and eyes 15 fastened. Therefore, by slipping on a single garment the wearer is ready for her gown or dress as the case may be.

The invention may be embodied in other specific forms without departing from the essential characteristics thereof. The illustrated embodiment is intended to be illustrative rather than 15 restrictive, the scope of the invention being delineated by the appended claim, and all equivalents are intended to be embraced therein.

I claim as my invention:

20 A combination undergarment comprising an upper waist section, a skirt and a step-in, said upper waist section having a single pair of shoulder straps and extending to substantially the hip-

line and being composed of elastic material cut and joined to closely fit and confine the upper part of the body and afford support for the busts and the waist-line region of the wearer, said upper waist section having a rear vertical opening extending from the top edge thereof to substantially the bottom thereof, a plurality of fastening devices for detachably securing the edges of said opening together, said skirt and said step-in being stitched to the lower edge of said upper waist section, to thereby cause them to lie smoothly over the body without wrinkling or bunching, said step-in comprising a front piece and a rear piece extending substantially the full width of the garment at their upper edges and tapering downwardly and detachably secured together at their free ends to provide a narrow crotch engaging portion, said skirt depending a considerable distance below said step-in and being of a length comparable to dress lengths to thereby function 20 as a petticoat.

LILLIAN B. PRUETT.
